UNITED STATES PATENT OFFICE

EDWARD A. BEILER, OF DUBUQUE, IOWA

BODY SUPPORT FOR COFFINS

Application filed June 19, 1930. Serial No. 462,345.

This invention relates to new and useful improvements in corpse supports for coffins, and more particularly to a support which can be readily adjusted to properly position the body.

During the course of the following specification and claims, numerous important objects and advantages will become apparent to the reader.

10 In the drawing:—

Figure 1 represents a side elevational view of the coffin with a portion thereof broken away and disclosing the invention mounted therein.

15 Fig. 2 represents a top plan view of the coffin showing the novel support mounted therein.

Fig. 3 represents a side elevational view of one of the elements of the invention.

20 Fig. 4 represents a fragmentary perspective view of the invention.

Referring to the drawings wherein like numerals designate like parts, it can be seen that numeral 5 represents the base of the coffin, while numeral 6 represents the side walls thereof.

25 In carrying out the present invention, an inverted U-shaped bracket 7 is employed having teeth 8 along each of its leg portions 9.

30 A V-shaped brace 10 is secured at its ends to the legs 9 and at its apex to the bight portion of the bracket 7. Angle members 11 serve to secure the U-shaped bracket 7 to the base 5 of the coffin, so that the same can be swung.

35 In conjunction with the U-shaped bracket 7, the boards 12 and 13 are employed, and hingedly connected together by hinges 14. The board 13 is elongated and curved at one end as at 15, while the board 12 is relatively

40 wide at the portion thereof which is connected hingedly to the board 13, but has an elongated leg 16 for disposition in spaced parallel relation to the adjacent portion of the board 13. The free end portion of the

45 leg 16 is hingedly connected to the base 5 of

the coffin as at 17, thus maintaining the opposite end of the board 12 in close proximity to the bracket 7.

A transversely extending plate 18 is provided on the bottom side of the board 12 so as to project beyond the end thereof and that portion of the plate 18 which projects beyond the board 12 is curved downwardly in the manner clearly shown in Fig. 4. This curved portion of the plate 18 is to engage with the teeth 8 of the bracket 7, for supporting the boards 12 and 13 in the proper inclined position, as is apparent in Fig. 1.

As is clearly shown in Fig. 4, the board 12 is provided with a pivotal toothed bar 19, the teeth of which are engageable with the pintle 20 on the adjacent end of the board 13. Thus the boards 13 may be maintained in an inclined position with respect to the board 12.

It will be observed in Fig. 2, that the board 12 is notched out to accommodate the bar 19 so that the bar will not interfere with the plate 18.

Obviously, the body may be properly inclined by suitably inclining the boards 12 and 13 by adjusting the plate 18 with respect to the teeth 8, and furthermore the body on the support may be tilted laterally with the assistance of the adjustable board 13.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

1. A body support for coffins comprising a board hingedly connected to the coffin at one end thereof, a toothed upright on the coffin at the opposite end of the board, means on the board for adjusted engagement with the teeth of the upright, said board comprising a pair of hingedly connected sections,

means whereby said sections may be maintained in inclined relation with respect to each other, and comprising a pivotally mounted toothed bar on one of the sections and a pin on the complementary section, with
5 which the toothed bar is engageable.

2. A body support for coffins comprising a board hingedly connected at one end to the coffin, a pivotally mounted rack bar, the said board at its free end being engageable with
10 the teeth of the rack bar.

In testimony whereof I affix my signature.
EDWARD A. BEILER.
